PUNCH OR TOOL HOLDING APPARATUS

Bhertel C. Rost, Foxboro, Mass., assignor to The Foxboro Company, Foxboro, Mass., a corporation of Massachusetts

Application January 9, 1937, Serial No. 119,758

5 Claims. (Cl. 164—118)

The present invention relates to an improvement in punch or tool holders wherein a tool, as a punch, cutter, or other implement may be more accurately and readily set or adjusted to predetermine the position of an area to be operated on thereby or of a hole or perforation to be punched. For example, in printing recording instrument charts or the like having a central opening and chart markings on both sides concentric therewith, the present invention facilitates obtaining printings on both sides which are accurately concentric with the central opening, particularly in a method where one side of the chart is printed and the chart sheets perforated at the same time, such, for example, as that more fully described in the co-pending application of Arthur G. Beal and Bernard Holmberg, Serial No. 62,846 filed February 7, 1936.

One embodiment of my invention is illustrated in the drawing attached to and forming a part of the present specification and wherein—

Figure 1 is a top plan view; and

Figure 2 a central transverse section.

As shown in said drawing and as applied more particularly to the making of recording instrument charts, apparatus embodying my invention includes a base or support in the form of a plate 1 adapted to be secured to the bed of a printing press or the like and provided with conventional means as clips 3 cooperating with recesses 3' for retaining a cut 2 or printing plate in position thereon for printing. Ordinarily, a cut for printing recording instrument charts is provided with a central opening accurately concentric with the circular chart markings represented on the cut. Economical and effective printing of charts of this type involves punching the central opening of the chart sheet simultaneously with printing the chart markings on one side thereof. It is one of the objects of my invention to provide means whereby the perforating cutter or punch may be assembled and adjusted in such relation to the bed-plate of the printing press and to the cut 2, for example that the markings printed by said cut will be concentric with the central opening in the printed chart sheet punched by the perforating cutter.

For this purpose, the plate 1 has an opening or bore 4 enlarged at its inner end to receive the annular flange 5 of an adjustable punch carrier in the form of a hollow sleeve 6 of substantially square cross-sectional contour and to allow for transverse adjustment of said sleeve in bore 4 when necessary to make said sleeve and therefore a punch, as 12, carried thereby concentric with

chart markings on the cut. In the apparatus shown, plate 1 is provided with two sets of opposed radial guide ways as drill holes 7 and 7', spaced 90° apart and each extending from an outer edge of the plate to said bore 4. Each hole 7 houses and guides a sleeve retainer in the form of a plunger 8 having an enlarged inner end forming a head which bears yieldingly against a peripheral flat side of sleeve 6; and each guide hole 7' accommodates a similar plunger 8' of which the head bears rigidly against sleeve 6 in opposition to one of said yielding heads. A set screw 9, Figure 1, is threaded in the outer end of each guide hole 7' and a plug 10 is secured in the outer end of each guide hole 7. A spring 11 is interposed between the opposed ends of each plunger 8 and the corresponding plug 10 respectively in each guide hole 7; and a rod 11' is similarly arranged between each set screw 9 and plunger 8' in each guide hole 7'. 20

The punch carrier or sleeve 6 is adjustably supported in position in bore 4 by the two plungers 8 biased toward said carrier by springs 11 and the two plungers 8', and is capable of transverse adjustment therein to obtain concentricity 25 with the chart markings of the cut to be printed from, by appropriate manipulation of the set screws 9 in cooperation with said base and said springs 11, this arrangement being effective in obtaining extremely fine and accurately controlled adjustments. 30

A hollow cylindrical punch or die 12 is fitted snugly into the cylindrical bore of sleeve 6 so that its cutting position is determined by the above described adjustment of sleeve 6 transversely in relation to bore 4. 35

I claim:

1. Punching apparatus comprising a base, a punch carrier, opposed carrier holders mounted on said base and one of which is spring pressed 40 to retain said carrier between them, and means cooperating with the base and said holders to adjust the position of the punch carrier in relation to the base.

2. Punching apparatus comprising a base, a punch carrier, opposed carrier holders slidably mounted on said base, a set screw threaded in said base and cooperating with said carrier holders to adjust the position of the punch carrier in relation to the base, and a spring arranged to press one of said holders yieldingly against a side of said carrier. 45

3. Punching apparatus comprising a base, said base having a central bore and radially disposed recesses spaced 90° apart and opening into said 50 55

bore, a punch carrier adapted to be adjustably supported in said bore, carrier holders slidably mounted in said recesses, and means cooperating with said base and with said holders to adjust the position of the punch carrier transversely in said bore.

4. Punching apparatus comprising a base, a punch carrier, a plurality of sets of opposed carrier holders mounted on said base, each of said sets including opposed slidable holders with end portions arranged to engage the carrier on opposite sides thereof, a compression spring bearing against the other end portion of one of said holders of each set, and a set screw co-operating with the base and with the other end portion of the other holder to adjust the position thereof

and of the punch carrier in relation to the base.

5. Tool holding apparatus comprising a base, guide ways provided by said base each open at one end and with the end opening of one guide way spaced from and opposite the end opening of the other guide way, plungers mounted in said end openings to move toward and from each other, one of said plungers being biased toward the other, a tool carrier mounted between said plungers, and means cooperating with the base and movable endwise against one of said plungers to vary the position of said carrier between the spaced end openings of said guide ways.

BHERTEL C. ROST. 15
